AUTOMATIC FIREARM WITH TWO CARTRIDGE MAGAZINES

Application filed June 4, 1929, Serial No. 368,396, and in Germany January 31, 1929.

The invention consists in improvements in or modifications of the invention described in Patent No. 1,709,399, in which two magazines for cartridges are provided and in which after one magazine has been emptied on firing and ejected, the second is automatically switched into the position for continuing the feeding of the cartridges.

The object of the present invention is, on the one hand to make the weapon adapted for using the ordinary magazines, in which, in known manner, the foremost cartridge is held by the inwardly bent lips of the open end of the magazine and is seized by the parts of the breech at the commencement of their forward movement and taken by them in the shortest path into the barrel. Also, according to the invention, the insertion of the filled magazine into the weapon is facilitated and is relieved from the energy necessary for ejecting the emptied magazine.

The invention enables these results to be obtained by the construction of the automatic device for changing over the magazines and the relative arrangement of the two magazines inserted in the magazine holder. For that purpose the foremost cartridge of the magazine which is at that time feeding the cartridges, lies within the range of movement of parts of the weapon introducing the cartridge into the barrel, while the second magazine is in a preparatory position, from which, after the automatic ejection of the first magazine when emptied, it is automatically brought into the feeding position by a suitable shift apparatus.

Preferably, the two magazines are arranged relatively to one another in a V formation, radially to the axis of the bore of the barrel. The energy for ejecting an emptied magazine and for bringing the second filled magazine from its preparatory position is provided by the kinetic energy (in the rearward or forward direction) of the parts of the weapon moved on firing. The parts effecting the al-

ternate insertion and removal of the two magazines are connected by a device set in motion by the energy imparted on firing to a change over coupling which is controlled in dependence on the condition of the cartridges of the magazine which is at that time in the feeding position.

The accompanying drawings represent an example of a construction according to the invention as applied to an automatic firearm with a recoiling barrel.

Figure 1 is a longitudinal section through the magazine chamber.

Figures 2 to 6 represent different cross-sections through the magazine chamber in which;

Figure 2 is a cross-section on the line A—A;

Figure 3 is a cross-section on the line B—B;

Figure 4 is a section on the line C—C and

Figure 5 is a section on the line D—D of Figure 1.

Figure 6 is a section on the line E—E of Figure 2.

Figures 7 to 9 show a second example of the automatic magazine changing apparatus.

The magazine chambers

The magazine chamber *c* is arranged laterally on the casing *b* of the weapon which serves as a guide for the barrel and the breech sleeve *a* connected with it; the chamber *c* is divided into two parts *c*₀, *c*₁ each of which receives a magazine *d* and which are arranged in V formation relatively to one another and are radial to the bore of the barrel. Pocket shaped members *c*₂ (Figure 2) are provided on a longitudinal wall of each chamber *c*₀, *c*₁ for the free movement of projections of the magazine. The chambers *c*₀, *c*₁ terminate in a common inlet opening *a*₁ of the breech sleeve *a*. The length of this opening *a*₁ is such that it extends during the whole recoil of the barrel over the magazine *d*.

chamber and the magazines can project in their forward operating positions with their lips retaining the cartridge into the opening a_1 without obstructing the movement of the barrel. A wedge-shaped member c_4 (Figure 2) is disposed in the space, closed externally by a wall c_3 , between the two chambers c_0, c_1 and serves for guiding the magazines and for containing the means for locking the magazines. The casing c of the chamber contains at its rear portion c_5 (Figure 1) a locking device for the breech and the apparatus controlling the alternate change over of the magazines. A continuation c_6 of the casing contains the ejector apparatus and the apparatus for effecting the change over movements of the magazines initiated by the movement of the breech sleeve a .

20 *The magazine and its locking device in the magazine chamber*

The magazines d are ordinary sheet box magazines with fixed retaining lips d_1 for the cartridges at the open end from which the foremost of the cartridges is moved under the action of a spring d_2 by a feeding device d_3 into the path of the recoiling breech piece is seized on the forward movement of the breech in known manner and is advanced into the position in the barrel. The device d_3 (Figure 1) carries on its side a lug d_4 , which projects through a slot d_5 of the wall of the magazine, is displaced forward on charging the cartridges into the magazine pocket c_2 and after the ejection of the last cartridge from the magazine unlocks the emptied magazine which was previously locked by a lever e . Two lugs d_6, d_7 (Figure 3) are arranged one over the other on the small sides of each of the magazine chambers and co-operate, for the purpose of alternately changing over the two magazines, with two-armed cam levers f, f_1 on a spindle f_0 (Figure 1) disposed between the chambers c_0, c_1 parallel to the axis of the bore of the weapon. The lugs d_7 are set back so far from the lugs d_6 of the cam levers f, f_1 that when, for example, one magazine is advanced into the firing position, that is, with its foremost cartridge in the path of the breech piece, the second magazine with lug d_7 can be displaced past the catch f_8 of the cam lever f until its broad lug d_6 engages with the catch f_8 .

55 In this preparatory position in which the open end of the magazine still lies outside the breech sleeve a , it is prevented from falling out by the two part locking lever e, e_3 (Figure 2). The locking lever has two projections e_2, e_1 extending into the path of a magazine lug d_8 (Figure 2); the projections are adapted to be swung together out of the locking position against the resistance of a spring by pressure from the side of the magazine on the projection e_1 and by pressure

on the locking lever e . A magazine is held in the above-mentioned preparatory position by the engagement of the magazine lug d_8 behind the projection e_2 ; when a magazine is pushed forward into the firing position, its lug d_8 is supported by the second projection e_1 . The unlocking of a magazine in the firing position is effected by the lug d_4 of the feeding device d_3 which, after the last cartridge has been pushed forward out of the magazine lips for retaining the cartridges, is pushed under the lug e_1 and raises the lever e, e_3 .

80 *Apparatus for the alternate change over by the movement of the breech sleeve on firing, of the two magazines inserted in the magazine chambers*

The change over of a filled magazine from the preparatory position into that for feeding a cartridge into the firing position in the barrel is effected automatically by means of the shaft f_0 (Figure 3) by displacement towards the breech sleeve, while at the same time the emptied magazine, unlocked by the lug d_4 , is moved away.

The levers f, f_1 are switched over by the recoil movement of the breech sleeve a . A lever g_1 , keyed on the shaft g_0 in the casing c_6 , is guided in a suitably curved groove, not shown, of the breech sleeve a which on the movements of the barrel imparts to the lever g_1 a pendulous oscillation which is transmitted as partial rotations in opposite directions to the shaft g_0 . This movement is 100 temporarily transmitted to the shaft f_0 in order to change over the magazines by means of change couplings, described more fully later, which are controlled in dependence on the condition of the cartridges of the magazine which is at that time in the feeding position. A lever g_2 secured on the front end of the shaft g_0 (Figure 5) has a slot g_3 at right angles to the shaft g_0 , in which slot a two-armed lever g_4 is mounted so as to oscillate about a pin g_5 at right angles to the shaft g_0 . The lever f_1 on the rear end of the shaft f_0 carries at its front side two symmetrically arranged projections f_2 on the shaft f_0 , of which one always, according to 110 the position imparted to the lever g_4 , lies in the range of oscillation of this lever oscillating in a vertical plane by the rotation of the shaft g_0 . The shaft f_0 consequently receives a single angular rotation in the one 115 or other direction, while the further oscillations of the lever g_4 , until it is changed over, have no effect on the shaft f_0 .

The change over of the lever g_4 is effected in dependence on the position of the lug d_4 of the magazine which at that time is in the feeding position when the lug d_4 has attained its most forward position, which occurs after the last cartridge has been 125 pushed past the lips of the magazine. The 130

lug d_4 then engages with and rotates an angular lever h mounted in front of it in the magazine casing. This rotation is transmitted by rods h_0 or h_1 to a double-armed lever h_3 which can oscillate about a vertical pin h_2 on the shaft g_0 . To one arm of the lever h_3 is linked the rod h_0 (projecting from one magazine) and to the second arm the rod h_1 (extending from the second magazine). On the arms of the lever h_3 are arranged, parallel to the pin h_2 , pin-formed projections h_4 which pass through corresponding recesses of the casing c_5 and lie in contact with the two arms of the lever g_4 . When the lever h_3 is actuated by the lug d_4 of a magazine, the lever g_4 is angularly displaced so as to lie in the range of the lever f_1 which up to that time was free from the two projections f_2 , whereupon the shaft f_0 is actuated by the rotation of the shaft g_0 . Thereby, the emptied magazine, which at the same time has been unlocked by the lug d_4 , is ejected and the second magazine is brought into the feeding position, so that its foremost cartridge lies in the path of the forward moving breech members.

A catch bolt i (Figure 4) is mounted in the casing c_5 and in known manner serves for holding the breech piece in its rearward position. This bolt, according to the invention, is connected with the two magazines so that it is only brought into the locking position after both magazines have been emptied or removed from the feeding position; that is, after the last cartridge has been fired from the magazine at that time in the weapon it catches the recoiling breech and retains it until either a magazine provided with cartridges is inserted in the feeding position or the catch has been removed by hand. For this purpose, two double armed levers i_0 , i_1 engage, for example, in a recess of the spring bolt i_1 , a projection i_2 of one lever i_0 projecting into the path of a lug of the magazine introduced into the left magazine chamber (Figure 4), while a projection i_3 of the second lever i_1 engages similarly in the right magazine chamber. When a magazine in one of the two chambers is to be brought into the feeding position, by the engagement of a lug with the lever i_0 or i_1 , it rotates the latter, so that the catch bolt i is moved out of the path of the breech piece. If there is no magazine in the feeding position, the catch bolt i is automatically inserted in the locking position.

Figures 7 to 9 illustrate a modified construction of the magazine changing device.

The rear end of the shaft f_0 carrying the members for ejecting the magazine is coupled by toothed segments f_4 with a shaft f_5 on which two levers g_1 , g_2 are loosely mounted. These are folded together in the closed position like scissor-blades by an intermediate torsion spring, which is not shown, and

are spread apart against the action of the spring by the swinging outwards of one or both levers. A cam k tapered towards the rear end of the breech sleeve a co-operates with the levers g_1 , g_2 , the cam k being inserted on the recoil of the barrel between the levers so as to open them against the resistance of the torsion spring. The levers g_1 , g_2 carry on their hubs dogs which can be connected alternatively by co-operating dogs to two coupling sleeves l_0 , l_1 rigidly connected together by a rod l_2 . The sleeves l_0 , l_1 are axially displaceable but not rotatable on the rectangular sides of the shaft f_3 ; they alternately couple the levers g_1 or g_2 with the shaft f_3 and therewith also with the shaft f_0 . The change over of the sleeve l_0 for altering the direction of rotation of the shaft f_0 and for exchanging the magazines is effected in dependence on the condition of the cartridges of the magazine at that time in the charging position, in a manner similar to that of the apparatus shown in Figure 6, by a rod h_0 , h_1 , m , m_1 (Figures 9 and 8), which engages in a groove l_3 of the coupling l_0 , l_1 . A magazine emptied by the discharge of its cartridges controls by means of its lugs d_4 the couplings l_0 , l_1 . On the recoil of the barrel after the last cartridge has been fired, the lever (for example g_2) then coupled with the shaft f_3 imparts a partial rotation to the shaft f_0 , so that the empty magazine is ejected and the second is brought from the preparatory position into the feeding position. The coupled lever g_2 , since the gear f_0 , f_3 is locked, by the magazine held in the feeding position, remains in its outwardly displaced position, while the second lever g_1 as the firing is continued simply executes under the action of the breech sleeve cam k idle oscillations on the shaft f_3 . After the feeding magazine has been emptied, the coupling l_0 , l_1 is automatically changed over for ejecting the empty and again feeding a charged magazine.

Action of the weapon

The weapon is assumed to be not charged and the breech is held fast by the catch bolt i (Figure 1) in its rear position. Two charged magazines are inserted in the empty magazine chambers of the weapon, the one in the feeding position, the second in the preparatory position; both are then secured against falling out or unauthorized movement by the locking device e_1 , e_2 (Figure 2). The magazine in the feeding position has on insertion, by contact with the projections i_2 or i_3 (Figure 4), moved the device i for locking the breech out of the locking position. The breech piece in its forward movement takes with it the foremost cartridge into its position in the barrel; the weapon is then ready for firing.

On actuating the trigger, all the cartridges in the feeding position of the magazine are

fired. The shaft f_0 remains at that time at rest, while the parts of the operating mechanism (for example the shaft g_0 , coupling members g_1 , Figures 1 and 5) which are in the range of the reciprocating parts of the barrel, simply carry out idle movements. The empty cartridge cases are ejected by the ejector g . After the last cartridge has been removed from the retaining lips of a magazine, the lug d_4 moving forward with the cartridge feeder d_3 removes the magazine locking device e_1 and at the same time by contact with the lever h (Figure 6) switches over the coupling between the shaft f_0 and its operating mechanism. The shaft f_0 is now rotated, the empty unlocked magazine is ejected and the full magazine is brought from the preparatory into the feeding position. The change over process is completed by the action of the cartridges of the now emptied magazine, so that the firing of the cartridges of the second magazine is proceeded with without interruption. This process is repeated so long as a new magazine can be inserted instead of the one which is ejected.

I claim:

1. An automatic firearm having at least two magazine chambers and a cartridge magazine adapted for insertion in each chamber; means for locking one of said magazines in cartridge-feeding position; and means for securing the other magazine out of feeding position; means for unlocking the magazine from which the cartridges have been fired; and means responsive to the action of said unlocking means for ejecting said magazine and for automatically shifting the other magazine into feeding position.

2. An automatic firearm comprising a recoiling barrel and a breech sleeve movable therewith, and having at least two magazine chambers; a cartridge magazine adapted for insertion in each chamber; a cartridge feeder for each magazine and means for actuating the feeder; means for locking one of said magazines in cartridge-feeding position, and means for securing the other magazine out of feeding position; means for unlocking the magazine from which the cartridges have been fired; and means initiated by the action of the unlocking means and actuated by the breech sleeve on recoil movement of the barrel for ejecting the magazine from which the cartridges have been fired and automatically shifting the other magazine into feeding position.

3. An automatic firearm having at least two magazine chambers and a cartridge magazine adapted for insertion in each chamber; a cartridge feeder for each magazine and means for actuating the feeder; means for locking one of said magazines in cartridge-feeding position, and means for se-

curing the other magazine out of feeding position; means carried by the said feeder and operative on completion of the cartridge-feeding operation to unlock the magazine from feeding position; means for ejecting said magazine when empty; and means simultaneously operable with said last-named means for automatically shifting the other magazine into feeding position.

4. An automatic firearm comprising a recoiling barrel and a breech sleeve movable therewith, and having at least two magazine chambers; a cartridge magazine adapted for insertion in each chamber; a cartridge feeder for each magazine and means for actuating the feeder; means for locking one of said magazines in cartridge-feeding position, and means for securing the other magazine out of feeding position; means for ejecting the magazine from which the cartridges have been fired; and means responsive to the movement initiated by the breech sleeve on the recoil of the barrel to automatically shift the other magazine into feeding position.

5. An automatic firearm having a barrel and comprising at least two magazine chambers; cartridge magazines adapted for insertion in each chamber; means for securing one of said magazines in cartridge-feeding position, and means for securing the other magazine out of feeding position in their respective chambers, said chambers being disposed at an angle relative to one another and adapted to retain the said magazines in V-formation relative to one another and radially to the axis of the bore of the barrel.

6. An automatic firearm having a barrel and comprising at least two magazine chambers; cartridge magazines adapted for insertion in each chamber; means for securing one of said magazines in cartridge feeding position, and means for securing the other magazine out of feeding position; and means disposed between said chambers adapted to space and guide said magazine at an acute angle relative to one another and radially to the axis of the bore of the barrel.

7. An automatic firearm comprising a casing and having a recoiling barrel mounted for reciprocating movement in said casing; a breech sleeve carried by the barrel; at least two magazine chambers mounted on the casing, and a cartridge magazine adapted for insertion in each chamber; means for securing one of said magazines in cartridge-feeding position, and means for securing the other magazine out of feeding position; a cartridge feeder for each magazine and means for actuating the feeder; means carried by the feeder for unlocking a magazine when empty; means responsive to the action of the unlocking means and actuated by the recoil movement of the breech sleeve for

ejecting the empty magazine; a pair of double armed levers mounted for rocking movement between the magazine chambers, and means on each magazine to selectively actuate said levers; and a bolt mounted in the casing for locking and unlocking the breech sleeve, said bolt being actuated by either lever to automatically lock the breech sleeve in rearward position when the magazines are both out of feeding position.

5 In testimony whereof we have affixed our signatures.
